ATTORNEYS

UNITED STATES PATENT OFFICE.

JOHN MALCOLM MCNEILL, OF ST. JOSEPH, MISSOURI.

GRAVE MARKER.

Application filed June 1, 1925. Serial No. 34,125.

My invention relates to improvements in grave markers, and it consists in the combinations, constructions, and arrangements herein described and claimed.

5 An object of my invention is to provide a grave marker of the character described in which particularly novel means is employed for composing and displaying inscriptions pertaining to the deceased.

10 A further object of the invention is to provide a grave marker of the character described in which novel means is employed for supporting the inscription bearing tablet of the marker upon a standard, which standard is driven into the ground at the head of the grave.

15 A further object of my invention is to provide a grave marker of the type described that is simple in construction, neat in appearance, and which is thoroughly practical for the purpose intended.

20 Other objects and advantages will appear in the following specification, and the novel features of the invention will be particularly pointed out in the appended claim.

25 My invention is illustrated in the accompanying drawings forming a part of this application, in which

Figure 1 is a front elevation of an embodiment of my invention,

30 Figure 2 is a sectional view along the line 2--2 of Figure 1,

Figure 3 is a partial rear elevation of the device illustrated in Figure 1, and

35 Figure 4 is a fragmentary perspective view partially in section of the inscription plate.

40 In carrying out my invention I make use of a vertical standard 1. The standard 1 is substantially T-shaped in cross section, and has a sharp incision point 2 at the lowermost end thereof, by means of which the standard may be projected into the earth adjacent to the head of the grave.

45 A bolt 3 for the purpose of anchoring the standard is projected transversely through the standard at a point intended to lie beneath the surface of the ground, and a nut 4 serves to maintain the bolt 3 from dislodgement from the standard, and is preferably placed at the mid-point of the bolt, thus holding the bolt in a position with portions extending on either side of the standard.

50 A part of the standard is cut away at the

55 top, as shown at 5, leaving the flat or cross sectional portion unobstructed as shown at 6. The tablet portions of the grave marker consists in an ornamental frame 7, substantially rectangular in shape, having a hook-shaped portion 8 at the upper end thereof which is arranged to engage with the portion 6 of the standard and to partially receive the portion 6. The frame 7 has an inwardly extending flange 9 at the inner edge thereof, with which a second removable frame 11 is engaged. The frame 11 is disposed within the frame 7 by the projection thereof through the back of the frame 7 prior to engagement of the portion 8 with the portion 6 of the standard. The frame 11 has side walls 12 having rabbeted portions 13 at the upper and lower walls thereof for receiving a glass plate 14. The outer surface of the plate 14 is contiguous with the outermost edges of the wall 12, and therefore bears against the flange 9 when the frame 11 is projected within the frame 7.

55 A legend bearing plate 15 of particularly novel construction (see Figures 1 and 4) is disposed between the glass plate 14 and the adjacent wall of the frame 11. This legend bearing plate 15 has a plurality of parallel slots 16 extending substantially horizontally thereacross, by means of which small metal plates 17 bearing letters of the alphabet, numerals, and other legends 18, are secured to the plate. The plates 17 are secured to the plate by projecting the end portions 19 of the plates through the slots 16 and bending these portions back into engagement with the back of the plate 15, as shown in Figure 4.

60 Means for securing the frame 7, with its inner frame 11, in place, together with a glass plate 14 and the plate 15, is provided in screws 20 and 21 projected through the standard 1 and engaged with threaded bores provided in the frame 7 at the top and bottom of the frame, substantially as shown in Figure 3.

65 Rearwardly extending bosses 22 are provided on the rear wall of the frame 7 adjacent to each side of the standard 1 so as to preclude lateral movement of the frame and to insure the disposition of the frame at right angles to the standard 1. To further assure positioning of the frame with respect to the standard, an opening 23 is provided through the standard, adjacent to the screw 105

70 110

21, and a boss 24 is provided on the frame 7 that is adapted for projection through the bore 23.

From the foregoing description of the various parts of the device, the operation thereof may be readily understood. My improved grave marker's are delivered to the dealer, cemetery keeper, or person having such markers in custody for use or sale, with the plate 15 free of the smaller plate 17. A large assortment of plates having both capital and small letters and numerals are provided, and when a grave marker is to be used, the plates 17 bearing letters and numerals pertinent to the grave over which the marker is to be placed are disposed upon the plate 15 in the manner described which consists in projecting the portions 19 of the plates through the slots 16 and in bending the portions 19 back against the adjacent face of the plate.

The entire plate is then disposed in the recessed portion of the frame 11, and the glass plate 14 is disposed in the rabbeted portion 13 of the frame. The entire frame is then projected within the wall 7 and the hook member 8 of the frame 7 is engaged with the portion 6 of the standard.

The bosses 22 and 24 will serve to position the standard relative to the frame, and the

screws 20 and 21 are disposed in their proper places, as shown in Figure 3, and will effectively lock the frame against movement from the standard, and frame 11 against dislodgement from the frame 7.

85

I claim:

A grave marker of the character described comprising an upright standard arranged to be driven into the ground, an outer frame, an inner frame having a marginal wall on all sides and having a solid rear wall arranged for disposition within said outer frame, a legend bearing plate having a plurality of slots thereacross disposed within said inner frame, a plurality of smaller plates having legends thereon and having portions thereof projected through said slots and secured to the plate by turning the projected portions downwardly against the back of the legend-bearing plate, a glass plate forming a cover for the inner frame and resting upon rabbeted portions provided in the marginal walls of said inner frame, a hook-shaped portion integral with the upper edge of said outer frame, said upright standard adapted to be received in said hook-shaped portion, and means for rigidly securing said outer frame to said standard.
